CLAIM

The ornamental design for an automobile motor shaft disassembly and assembly tool, as shown and described.

DESCRIPTION

FIG. 1 is a front perspective view of an automobile motor shaft disassembly and assembly tool, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 3.

The evenly spaced broken lines in the drawings depict portions of the automobile motor shaft disassembly and assembly tool that form no part of the claimed design. The dash-dot-dash broken lines denote the boundaries of the enlargement and form no part of the claimed design.
